UNITED STATES PATENT OFFICE.

MARION A. WHARFIELD, OF TOLEDO, OHIO, ASSIGNOR OF EIGHT-FIFTEENTHS
TO BENSON G. McMECHEN AND HENRY C. WHARFIELD, OF TOLEDO, OHIO.

LINK-MOTION FOR STEAM-ENGINES.

SPECIFICATION forming part of Letters Patent No. 705,174, dated July 22, 1902.

Application filed December 9, 1901. Serial No. 85,165. (No model.)

To all whom it may concern:

Be it known that I, MARION A. WHARFIELD, a citizen of the United States, residing at Toledo, in the county of Lucas and State of Ohio, 5 have invented certain new and useful Improvements in Link-Motions for Steam-Engines; and I do declare the following to be a full, clear, and exact description of the invention, such as will enable others skilled in the 10 art to which it appertains to make and use the same, reference being had to the accompanying drawings, and to the figures of reference marked thereon, which form a part of this specification.

15 My invention relates to a link for controlling and reversing the movement of steam-valves for steam-engines; and its object is to provide a simple easily - controlled device whereby the valve shall be thrown into open 20 or closed position rapidly, thus giving a sharp cut-off and exhaust.

The further object of my invention is to reduce to a minimum the movements and vibration of the link.

25 I attain these objects by means of the devices and arrangement of parts hereinafter described, and shown and illustrated in the accompanying drawings, in which—

Figure 1 is a side elevation of an upright reciprocating steam-engine provided with my link-motion; Fig. 2, a side elevation of my device detached; Fig. 3, a side elevation of the pieces, hereinafter referred to, comprising my link; and Fig. 4, a central vertical transverse sectional elevation of the part shown in Fig. 3 in place, taken on line *xx*, Fig. 2.

Like numerals of reference indicate like parts throughout the drawings.

In the drawings, 1 is the crank-shaft of the 40 engine, driven by connecting-rod 2. Upon the crank-shaft is a single cam 3 and cam-strap 4. The latter is provided with an arm 5. 6 is an open link curved in the arc of a circle. Projecting at a right angle from the 45 middle of the link, on one side thereof, is a short shaft or wrist 7, which is journaled on a pillow-block 7^a, which is supported by the base of the engine. (See Fig. 4.) At the opposite end of this shaft and in a plane parallel 50 with the link is an arm 8, which is bent at a right angle, (see Fig. 3,) after the manner of

a bell-crank lever. At its angle this lever is enlarged and has an elongated opening 8^a, which is designed to receive and to embrace loosely the crank-shaft of the engine. The 55 link 6, the shaft 7, and the lever 8 are formed in one piece. The arm 5 of the cam 4 and the arm 8^b of the lever 8 lie side by side and at their extremities are pivotally connected together by means of a pin 8^c, projecting laterally from the extremity of the arm 8^b, which pin engages a corresponding hole in the extremity of the arm 5.

Secured in the curved slot of the link is a 60 sliding block 10, to which is pivotally secured 65 the valve-rod 11, which is connected with and controls the valve of the engine in the usual manner. 12 is a rod pivotally connected at one end to the block 10 and pivotally connected at its other end to the reversing-lever 70 13, which lever is adapted to move the block the full length of the link and determines the position of the block 10 relatively to the link 6. This lever is provided with a suitable 75 detent for holding it set at any desired position. In the example shown in the drawings the lever carries a small pinion 14, which meshes with and rides upon a toothed quadrant 15 and which is normally engaged by the detent 80 illustrated in dotted lines in Fig. 1.

The operation of my device is as follows: The parts being assembled as shown and described and steam being admitted to the engine through the valve-chamber, the throw of the valve and consequently the amount of 85 steam used will depend upon the position of the block 10 in relation to the link 6. This position is governed by means of the reversing-lever 13 in the usual manner. The throw of the arm 5 of the cam-strap 4 imparts a like 90 motion to the arm 8^b of the lever 8, causing the link to swing on its shaft in the arc of a circle. The shaft the end of which is secured to the side of the link exactly midway of its length forms a fixed fulcrum on which the 95 link swings, thus avoiding the complicated endwise and sidewise movements usual in link-motions. As the sliding block is moved by the reversing-lever the point of cut-off is varied or the steam is reversed or the valve 100 is rendered inactive, according to the position of the block, as may be required. When the

sliding block occupies a position in the link at any point between the middle and either end, it receives a motion great in proportion to its proximity to the end, and, conversely, 5 when the block is set at exactly the middle of the link the rod 11 ceases to reciprocate, the valve becomes inoperative, and the engine stops. By shifting the block from the position shown to the position indicated by the 10 dotted lines the admission of the steam and the motion of the engine are reversed.

It will be seen from the diagram in Fig. 2 that the movement of the extremities of the arms 5 and 8^b at the point where they are piv- 15 oted together is through a short arc of the circle of which shaft 7 is the center and that while the engine is making but a small part of a revolution the lever 8 is thrown. Hence the swing of the link upon its bearing is rapid.

20 The result is that the valve is moved quickly and the cut-off is clean.

It will be seen that the illustrated arrangement of the lever 88^b with the elongated opening 8^a for the reception of the crank-shaft 25 permits the lever to be disposed in the engine, so as to take but little room and to give strength and rigidity to the lever, permitting the lever to be swung without interference from the shaft.

30 Having described my invention, what I claim, and desire to secure by Letters Patent, is—

1. A link-motion comprising a link, a shaft projecting laterally from one side of the link 35 midway between the ends of the link, stationary bearings for said shaft, connections between the shaft of the engine and the link which connections give to the link a single uniform motion on its bearings in harmony

with the movement of the engine-shaft, a 40 block in the link connected with the engine-valve, and means for controlling the position of the block relatively to the link, the arrangement being such that the block may be moved into and out of coincidence with the axis of 45 motion of said link.

2. A link, stationary bearings on which the link rocks midway of its length and width, a cam on the engine-shaft set oppositely to the engine-crank, a cam-strap on the cam, and 50 pivotal connections between the cam-strap and the link which pivotal connections are disposed in a line at a right angle to the line of the axes of the link-bearings and the engine-shaft. 55

3. In a link-motion, a link, a shaft for said link projecting from one side thereof, the arrangement being such that the shaft's axial line, extended, passes through the longitudinal and transverse center of the link-opening, a stationary bearing for said shaft, a block slidably mounted in the link, and means for rocking the link on its shaft in harmony with the motion of the engine-shaft. 60

4. In a link-motion, a link, a shaft for said 65 link midway of its length, a lever connected with said shaft and having two arms at substantially a right angle to each other and in a plane parallel to the link and having at the angle of the arms an elongated opening for 70 the engine-shaft, said link, shaft and lever being integral.

In testimony whereof I affix my signature in presence of two witnesses.

MARION A. WHARFIELD.
